UNITED STATES PATENT OFFICE.

HARRY A. KUHN AND WALTER W. MACFARREN, OF PITTSBURGH, PENNSYLVANIA.

METHOD OF TUNNELING.

1,093,787.

Specification of Letters Patent.

Patented Apr. 21, 1914.

Application filed October 30, 1909. Serial No. 525,531.

To all whom it may concern:

Be it known that we, HARRY A. KUHN and WALTER W. MACFARREN, citizens of the United States, residing at Pittsburgh, in 5 the county of Allegheny, State of Pennsylvania, have invented a new Method of Tunneling, of which the following is a specification.

Our invention relates to a method of tunneling and more particularly to a method of tunneling in hard rock. Such tunnels are usually constructed by first driving a small pilot tunnel or "heading" of merely sufficient sectional area to admit men and 10 tools and for the removal of the material, this "heading" being subsequently enlarged to the desired size. When the finished cross section of the tunnel is small, the whole tunnel is frequently driven as a "heading." 15 The whole sectional area of the tunnel may be taken out by our improved method, or our method may be used in driving the "heading" only and the remainder of the rock may be removed in various ways. The 20 application of our improved method is, however, full and complete when applied to the "heading" only. A partly driven "heading" may be said to consist of two parts, the "head" and the "bore." The "head" 25 of the "heading" is the vertical face of the rock which closes one end of the "bore." The "bore" of the "heading" comprises the roof, floor and side walls or their equivalents extending from the "head" to the 30 open end of the "heading."

Briefly stated, our invention consists in a method of tunneling comprising the following steps: 1. Forming a number of intersecting slots or channels in the "head" thus 35 leaving the uncut portions between said slots in the condition of blocks hanging by one end only. 2. Dislodging said hanging blocks by the application of a suitable force or forces. 3. Removing the dislodged material from the "heading" or tunnel.

Where great speed is desirable, as is usually the case in such work our improved method of tunneling would include the following refinements: 1st. Forming one half 40 of the said channels or slots in the "head" simultaneously. 2nd. Forming the said channels or slots alternately on the second half of the "head" during which operation the rock would be dislodged and removed from the first half of the "head." 45 By the above two processes the machinery

or laborers used for cutting slots can be kept continually employed and the "head" can, therefore, be advanced continuously.

Referring to the drawing, Figure 1 is a 60 diagram illustrating in elevation the channels or slots to be formed on one half of the "head." Fig. 2 is a diagram illustrating in elevation the channels or slots required to be formed on the full face of a 65 tunnel of the usual rectangular cross section with an arched roof, and Fig. 3 is a plan view showing the condition of the "head" at the conclusion of the formation of one half of the channels or slots.

In Fig. 1 the horizontal channels, 1, 2, 3, and 4 intersect the vertical channels, 5, 6, 7 and 8 leaving the blocks 9 hanging to the original bed of rock by one end only. As a matter of convenience, especially where machinery is employed for forming the channels, it is advisable to proportion the "head" 70 so that its cross section will be a rectangle composed of two equal squares. The diagram Fig. 1 illustrates the channels to be 75 formed in one of these squares and the rock to be removed therefrom after the channels are formed.

In Fig. 2 the arrangement shown covers the full cross section of a large tunnel in 80 which the blocks 9 cover one half of the "head," and blocks 10 the other half of the "head" and the blocks 11, 12 and 13 material above the "head," which is preferably 85 taken down after the "head" has been advanced some distance as it may then be 90 loaded directly into cars without reaching the ground.

In Fig. 3 at the left side of the "head" the channels 5, 6, 7 and 8 are shown as just 95 having been completed to their full depth.

The dotted line 14 may represent the bottom of the channels 1, 2, 3, and 4. On the right side of the "head" the blocks 9 have been broken off at the clearance line 15 and 100 removed. The "head" as shown in Fig. 3 is now ready for the blocks 9 on the left side, of the "heading" to be broken off and removed while at the same time the channels 1, 2, 3, 4, 5, 6, 7 and 8 are cut in the right 105 side of the "head;" at the conclusion of which operation the conditions will be the same as shown in Fig. 3 only reversed as regards the two halves of the "head."

From the above description, it will be 110 clearly seen that we have provided a simple and efficient method of tunneling in hard

rock, which may be either carried out by manual labor with hand tools, or by any suitable rock channeling machinery. It will be noted that a tunnel of any cross section and length can be cut by our improved method without the use of explosives, there being no blasting operation. It will also be noted that only a small per centage of the rock is actually disintegrated into fine cuttings and that therefore, the power required to effect this disintegration is the minimum, and further that when the cross section of the tunnel is divided as shown by intersecting channels of regular outline and spacing, the material removed is in the form of rectangular blocks of stone, suitable for use in building any sort of large masonry.

It can be shown that with improved machinery this method of tunneling will permit of tunnels being driven at a greater rate of speed than any method now in practical use so far as we are aware.

We claim—

1. A method of tunneling comprising the following steps: 1st, forming simultaneously a number of intersecting slots or channels in one half of the "head"; 2nd, forming simultaneously similar slots or channels in the other half of the "head" and at the same time removing the material previously cut, and the material between said previous cuts in the first half of the "head", and so on alternately "*ad libitum*."

2. The method of continuously advancing a tunnel "heading" comprising the alternate operations of forming slots in the left half of the "head" to prepare the rock for dislodgment, and at the same time dislodging and removing the rock at the right half of the "head," and then forming similar slots at the right half of the "head" while simultaneously dislodging and removing the rock from the left half of the "head."

3. A method of tunneling comprising the

formation of intersecting channels or slots 45 of uniform depth in the "head" said slots being parallel to the bore of the tunnel and at regular intervals, and then breaking out the blocks of stone between said slots, whereby the major part of the excavated material 50 is removed in pieces of regular size and shape suitable for building purposes.

4. A method of tunneling comprising the following steps: 1st, driving a lower "heading" the full width of the tunnel; 2nd, separating the material to be excavated above said "heading" into blocks hanging by one end only; 3rd, breaking off said blocks by the application of a suitable force or forces; 4th, removing said blocks from the tunnel. 60

5. A method of tunneling comprising the following steps: 1st, driving a lower "heading" of the full width of the tunnel; 2nd, separating the material to be excavated above said "heading" into blocks hanging 65 by one end only; 3rd, breaking off said blocks by the application of a suitable force or forces; 4th, dropping or lowering said blocks into cars placed under the same; 5th, removing said blocks from the tunnel. 70

6. A method of rock tunneling comprising the following steps: 1st, driving a "heading" the full width of the tunnel by forming intersecting slots or channels in the "head" and then dislodging and removing 75 the rock between said slots; 2nd, beginning at a point some distance in the rear of the "head" and enlarging the tunnel by forming intersecting slots or channels above the "heading" and then dislodging and removing 80 the rock between the said slots simultaneously with the driving of the "heading."
